UNITED STATES PATENT OFFICE.

HARRY W. MELDRUM, OF EAST ST. LOUIS, ILLINOIS.

WRENCH.

1,015,970.

Specification of Letters Patent.

Patented Jan. 30, 1912.

Application filed February 11, 1911. Serial No. 608,011.

To all whom it may concern:

Be it known that I, HARRY W. MELDRUM, a citizen of the United States, residing at East St. Louis, in the county of St. Clair 5 and State of Illinois, have invented certain new and useful Improvements in Wrenches; and I do hereby declare the following to be a full, clear, and exact description of the invention, such as will enable others skilled in 10 the art to which it appertains to make and use the same.

My invention relates to new and useful improvements in wrenches and more particularly to a combination wrench designed 15 for all the various purposes usually subserved by a pipe and nut wrench, as separately constructed, and my invention consists in certain novel features of construction and combination of parts, the preferred form 20 whereof will be hereinafter clearly set forth and pointed out in the claim.

The object of my invention, among others, is to provide a combination wrench suitable 25 for use upon nuts of various size and also for reliably efficient action upon pipes of varying diameter.

In the accompanying drawings, Figure 1 is a side elevation of my wrench complete, while, Fig. 2 shows a longitudinal sectional 30 view of the movable jaw on a slightly enlarged scale from that presented in Fig. 1.

Referring by numerals to the various details of my invention and coöperating accessories, 1 indicates the handle proper having 35 the preferably integral head or fixed jaw 2, one end of which is adapted for action upon nuts, while the other end is provided with a plurality of teeth or corrugations 3 for action upon pipes, rods, and the like.

40 Designed to coöperate with the fixed jaw or head, is a movable jaw 4 having a central opening of proper size to loosely move upon the handle 1, the latter being provided upon one edge with a plurality of ratchet teeth 45 designed to coöperate with the ratchet teeth upon a movable or adjustable wedge member 6, while the outer edge of said wedge member is tapered to fit a corresponding seat within the jaw 4, as clearly 50 shown in Fig. 2. The adjustable wedge member 6 is held within its seat, thus provided in the movable jaw, so that it may not casually drop out of its operative position, by means of a pin 7 permanently secured 55 thereto and extending through an opening or slot 8 in a contiguous part of the movable

jaw, as shown in Fig. 2, the said pin having a suitable handle or terminal 9, as clearly shown. It will be obvious that the office performed by the wedge member 6 is to lock 60 the movable jaw at any desired point upon the handle member 1. The opposite end of the movable jaw 4 is also provided with a slotted opening 10 and seated within said opening is a spring member 11 anchored in 65 position in any preferred way, as by a screw 12.

To the operating face of the movable jaw, I mount the ratchet faced member 13 designed to coöperate with the ratchet face 3 70 of the fixed jaw, said member 13 being mounted upon the free end of the spring member 11, either permanently or removably, as by the anchoring screw 14, and it is therefore obvious that the space or opening 75 10 affords a limitation of movement for the said member 13, thus permitting said member 13 to accommodate itself to the strain placed thereon incident to the use of the pipe wrench.

As indicated by Fig. 1 of the drawings, it is obvious that the ratchet faced member 13 is so mounted that it may move outward incident to applying the wrench to a pipe or bolt, but will be normally drawn inward 85 by the action of the spring 11. It is further obvious that the said member 13 is limited in its outer movement by the extent of the opening 10.

It is thought from the foregoing, that the 90 operation or manner of using my improved wrench will be clearly apparent, though it may be stated that the movable jaw may be readily moved upon the handle portion by withdrawing the wedge member 6, and when 95 the movable jaw has thus been adjusted in the desired position, said wedge member is forced home in its seat, thereby causing the ratchet teeth thereon to coöperate with the ratchet teeth 5 upon the handle.

100 It will thus be seen that I have produced a wrench of reliable efficiency designed for the double purpose of operation upon nuts, square rods and the like and also upon pipes, bolts, etc.

105 What I claim is:—

A wrench comprising a handle portion, a fixed jaw on the handle and having a toothed face, a movable jaw slidable thereon provided with a longitudinal recess substantially parallel therewith, an auxiliary toothed member comprising a wedge shaped 110

block seated loosely on the face of the movable jaw opposite the toothed face of the fixed jaw, and a spring secured to the inner face of the auxiliary toothed member, extending through said longitudinal slot, and attached to the outer surface of the movable jaw.

In testimony whereof I have signed my name to this specification in the presence of two subscribing witnesses.

HARRY W. MELDRUM.
